UNITED STATES PATENT OFFICE.

BAXTER D. WHITNEY, OF WINCHENDON, MASSACHUSETTS.

MACHINE FOR SMOOTHING PLANED WOODEN SURFACES.

Specification of Letters Patent No. 17,992, dated August 11, 1857.

To all whom it may concern:

Be it known that I, BAXTER D. WHITNEY, of Winchendon, in the county of Worcester and State of Massachusetts, have invented 5 an Improved Machine for Smoothing Surfaces of Wood, of which the following is a full, clear, and exact description, reference being had to the accompanying drawings, making part of this specification, in 10 which—

Figure 1 is a plan. Fig. 2 a side elevation. Fig. 3 an end view. Fig. 4 a longitudinal vertical section on the line x, x , of Fig. 1. Fig. 5 a section on the line y, y of Fig. 1, showing details to be referred to. Fig. 6 a view of the under side of the carriage.

The object of my present invention is to obtain a machine that will be capable of 20 smoothing the surfaces of boards and similar stuff, whether such stuff has been previously reduced to a uniform thickness and perfectly plane surface or not; and this I accomplish by allowing the block which carries the scraper or smoothing knife to have 25 a small amount of vibration to accommodate to any inequalities in the surface to be smoothed, while the stuff rests on a rigid plane bed or carriage.

30 This machine will be found particularly well adapted to smooth the surfaces of thin stuff such as is used for the hoop or sides of light wooden boxes (cheese boxes &c.) and veneered stuff.

35 To enable others skilled in the art to understand and use my invention I will proceed to describe the manner in which I have carried it out.

In the drawings A is the cast iron frame 40 or bed of the machine, this consists of a pedestal 1 and two side pieces 2 and 3 with a space between (see Fig. 1). In each of these pieces 1 and 2 near their top is a groove a Fig. 4 in which slides a plane rigid 45 carriage B to the under side of which is attached the rack bar b that engages with a pinion C on a shaft D. This shaft passes through slots in the two sides of the frame A and has its bearings at one end in a sup-

50 port E attached to the outside of the part 2 of the frame A. This support is set off as shown in Fig. 1 to accommodate the driving pulley F on the shaft D; the other end of the shaf D is carried by a hand lever G piv- 55 oted at c to the outside of the part 3 of the frame A. By this arrangement when the le-

ver G is in the position shown in Fig. 2 the pinion C is engaged with the rack b and as the pulley F is revolved in the direction of its arrow Fig. 1 the carriage B is caused to move in the direction of its arrow until the pinion and rack are thrown out of gear, which is done in the following manner: A lever H is pivoted at d to the frame A, it vibrates in a plane parallel to the side 60 thereof, and is held up by a spring I against a pin e projecting from the face of the lever G. When the lever G is in the position shown in Fig. 2 the pin e rests on a shoulder f on the lever H and thus the pinion and 65 rack are held in gear. A dog K is attached to the upper side of the carriage B near its rear end and projects over the side of the frame, so that as the carriage is moved along by the revolution of the pinion C the 70 dog K' strikes against the upper end of the lever H and trips it from under the pin e , this allows the lever G to drop by its weight and the weight of the shaft D and the pinion C is thrown out of contact with 75 the rack b and the carriage B is free to be drawn back by a weight attached to a cord running over a pulley L on the end of the frame A.

The stuff to be operated upon is clamped 80 to the carriage B in the following manner: The shank of the clamp M passes through a hole in the carriage B near its front end and is secured by a nut and screw to a lever N provided at i to standards projecting 85 down from the under side of the carriage; an arm O is attached to the lever N and hangs down from it in such a position that as the carriage is drawn back by the weight 90 into the position shown in Fig. 4 the arm O 95 shall strike against a stop P (seen dotted in Fig. 1) attached to the inside of the frame A by screws g passing through the side 3 of the frame; this causes the clamp M to be raised against the resistance of the spring Q 100 which is secured to the under side of the carriage and laps over the end of the longer arm of the lever N as shown in Fig. 6 and the piece of stuff is released from the 105 clamp M.

To enable the operator to raise the clamp M at pleasure for the purpose of inserting a piece of stuff I have adopted the following device. A spring stop R (Figs. 5 and 6) is attached at one end at h to the underside 110 of the carriage B; a hand lever S with a short arm k bent up at right angles is piv-

oted at l to the inner face of side 2 of the frame A, as the carriage is drawn back by the weight, the shoulder m of the spring R passes over the end of the arm k , now by 5 pressing down on the hand lever S the carriage is forced back a little farther and the pressure of the arm O against the stop P raises the clamp M as before explained.

The block U which carries the smoothing 10 knife or scraper n is pivoted at o in the middle of its length to a link p attached to a lever V, the block U has a hole near each end, up through which pass loosely the pins 15 or round standards r rising from each side of the top of the frame A, this allows the block U to be raised and lowered vertically by the lever V at the same time that it has a slight vibration on the pivot o that it may accommodate itself to any variation in 20 thickness of the sides of the stuff operated upon.

The scraper n is formed as shown in section in Fig. 4 with the edge turned forward 25 against the direction in which the carriage B travels when the scraper is operating, and acts in a manner similar to the well known tool of the cabinet maker. The lever V is pivoted at q (Fig. 3) to a standard W rising from the top of the frame A and 30 is drawn down by a spring X attached to the opposite side of the top of the frame, this keeps the scraper n in contact with the surface of the stuff while it is being drawn under it. Toward the other end of the 35 lever V is pivoted at s a rod Y which is connected at t by a screw and slot to the hand lever G. Thus as the lever G is dropped by tripping the lever H, the lever V is vibrated by the rod Y against the resistance 40 of the spring X and the block U is raised out of contact with the piece of stuff on the carriage.

If the weight of the lever G and shaft D are not found sufficient a spring may be attached to the outer end of the lever G and to the frame A.

The nut and screw on the shank of the

clamp M allows of its adjustment for thicker or thinner stuff.

The machine is operated in the following 50 manner: The shaft D is driven by the drum F in the direction of the arrow, the pinion C being disengaged from the rack bar b; the carriage being in the position shown in the drawings, the hand lever S is depressed, 55 this as explained raises the clamp M the piece of stuff to be smoothed is laid on the carriage with one end under the clamp, which holds it when the lever S is relieved. The lever G is now raised into the position 60 shown in Fig. 2 where it is supported by the lever H this engages the pinion C with the rack b and the carriage B is drawn along under the scraper n the lifting of the lever G having allowed the spring X to 65 draw down the lever V and bring the block U down onto the stuff. I may here mention that the slot at t in the end of the rod Y allows a slight play to the lever V that the block U may accommodate itself to the inequalities of the surface of the stuff operated on. The carriage B is moved forward by the pinion C until the dog K attached 70 to it comes in contact with the lever H when this lever is tripped from under the lever G which is allowed to drop, and the pinion C falls out of gear with the rack b when the carriage is free to be drawn back by the weight attached to the cord over the pulley L into the position shown in Fig. 4 when 75 the arm O strikes against the stop P which 80 raises the clamp M against the resistance of the spring Q and releases the piece of stuff.

What I claim as my invention and desire to secure by Letters Patent is—

The scraper n pivoted and operating in the manner substantially as described in combination with a mechanism for the purpose of carrying the wood forward in contact with the scraper.

BAXTER D. WHITNEY.
